UNITED STATES PATENT OFFICE.

DAVID WEISS, OF NEW YORK, N. Y.

DETACHABLE HEEL.

1,157,476.

Specification of Letters Patent.

Patented Oct. 19, 1915.

Application filed June 12, 1915. Serial No. 33,743.

To all whom it may concern:

Be it known that I, DAVID WEISS, citizen of the United States, residing at New York, in the county of New York and State of New York, have invented certain new and useful Improvements in Detachable Heels; and I do hereby declare the following to be a full, clear, and exact description of the invention, such as will enable others skilled in the art to which it appertains to make and use the same.

This invention relates to detachable heels for boots or shoes, and one of the principal objects of the invention is to provide simple means for securing a detachable heel to a shoe and to provide means whereby the heel may be readily detached from the shoe so that the heels may be interchanged to prevent wearing away upon one side, or to even up the heel.

Another object of the invention is to provide a detachable heel having a fastening device connected thereto which can be moved into locking or unlocking position to either hold the heel firmly to the shoe or to permit the same to be detached therefrom.

The foregoing and other objects may be attained by means of the construction illustrated in the accompanying drawing, in which—

Figure 1 is a top plan view of a detachable heel made in accordance with this invention, Fig. 2 is a bottom plan view of the heel seat portion of a sole, Fig. 3 is a longitudinal section through a heel and a portion of the sole, and Fig. 4 is a sectional view taken on the line 4—4 of Fig. 3 with the heel shown attached to the sole.

Referring to the drawing, the numeral 1 designates a shoe sole and connected to the heel portion 2 of the sole is a plate 3, said plate being substantially the shape of the heel seat, but considerably smaller, said plate being attached by means of suitable fastenings 4 and provided with a transverse slot or opening 5. The plate 3 is provided with a slightly upturned outer edge 6 disconnected from the heel seat. At the breast portion of the plate 3 is a leather strip 7 having a notch 8 therein at a central point, said strip 7 being connected by fasteners 9 to the heel seat portion of the sole.

The shoe heel 10 may be made of rubber or leather, or the body portion may be made

of leather and the top lift 11 may be of rubber.

Secured to the heel seat is a plate 12, slightly larger than the plate 3 and having a marginal flange 13 extending inward from the edge of the plate 12 to form a guide for the outer edge 6 of the plate 3. The plate 12 is secured to the heel seat by means of fastenings 14, and a heel rand 15 serves to make a tight joint between the heel and the sole when the heel is attached.

A pivoted latch or lock 16 comprising a wire having a straight shank extending into the heel from the heel breast 17 is provided with a T-head 18 which is disposed in a recess 19 in the heel located immediately over the slot 20 in the plate 12, and in coincidence with the slot 5 in the plate 3. The front end of the lock 16 is provided with a downturned handle or finger hold 21.

The heel can be quickly attached to the sole by sliding the heel forwardly to engage the outer edge 6 of the plate 3 under the flange 13, after the lock has been turned so that the T-head lies across the recess 19 and the slots 20 and 5. When the handle portion 21 of the lock is turned to one side or the other, the T-head 18 engages the slots 5 and 20 in the plates 3 and 12 to hold the heel firmly in place on the shoe.

From the foregoing it will be obvious that a detachable heel made in accordance with this invention can be quickly detached from a shoe and can be transposed with the heel of the other shoe to prevent wearing off at the sides or at least to even up the heels. It will be apparent also that a new heel made in accordance with this invention can be readily connected to a shoe after one has been worn out.

Various changes may be made in the details of construction without departing from the spirit and scope of the invention as defined in the claims.

What is claimed is—

1. A detachable heel construction comprising a plate connected to the heel seat portion of a sole, said plate having a slot therein extending transversely of said plate, a detachable heel section, a plate connected to said detachable heel, the plate having a marginal flange to receive the first named plate, said second named plate having a slot, said detachable heel having a recess in alignment with the slot, and a pivoted lock having a T-head to engage said slot when

turned and said lock having a finger hold at the breast of the heel.

2. A detachable heel construction comprising a plate connected to the heel portion of the sole, and having a slot therein, a detachable section, a plate connected to said detachable heel and having a recess alining with the slot in the first named plate, said plates adapted to engage one with the other,

and a pivoted lock having a T-head to engage the recess and slot in the two plates to hold them locked together. 10

In testimony whereof I affix my signature in presence of two witnesses.

DAVID WEISS.
